PAGE 2

FIG. 1 is a front perspective view taken from the top and one side of a support for potted plants embodying my new design.

FIG. 2 is a rear perspective view thereof taken from the bottom and side opposite that shown in FIG. 1.

FIG. 3 is a top plan view thereof.

FIG. 4 is an elevational view thereof taken from the side shown in FIG. 2.

FIG. 5 is an enlarged sectional view thereof taken on line 5—5 of FIG. 3, the broken line representation of a flower pot being included for purposes of illustration only.

I claim:
The ornamental design for a support for potted plants, as shown and described.
